AIR COOLING, CONDITIONING, AND CIRCULATING APPARATUS

William M. Bell, Evanston, Ill.

Application April 10, 1936, Serial No. 73,667

3 Claims. (Cl. 257—121)

This invention relates to improvements in air cooling, conditioning and circulating apparatus which is adaptable for use in homes, industrial plants and other buildings.

5 One of the objects of my invention is to provide apparatus of this character which shall be simple in construction, low in cost of installation and effective in use for the purposes intended.

An important object of my invention is found 10 in the provision of novel under-ground air-cooling channels, passages or conduits arranged to admit air therethrough to be cooled therein and then discharged into desired points or areas of a building; such air-cooling means including 15 means for filtering the air of dust and pollen or other matters, and a multiple speed motor-driven fan for regulating and controlling the passage of the air through the under-ground air-cooling channels and into and through the building.

20 Another object of the invention is found in the novel intake for under-ground air-cooling means which intake includes valve-controlled openings or passages for admitting air into the under-ground cooling means either from the basement 25 or one of the upper floors of the building or from a point outside of the building; such valves also being arranged to simultaneously admit air into the under-ground cooling means from any two or all of such points.

30 Another object of my invention resides in the novel construction and configuration of such under-ground cooling means whereby a maximum amount of cooling surface will be provided in a minimum of used or available space. The 35 cooling means can be made of tile, iron pipe, or any other suitable and preferably heat conductive material, as for instance copper or rust-resisting iron or steel.

Another object of the invention resides in the 40 provision of under-ground air-cooling means which will cause a circulation of the air in different directions in a minimum of confined space, as shown for instance in Figs. 3 and 4 where the air passes through interconnected semi-circular pipe 45 sections disposed in a vertical plane and arranged laterally in interconnected sections.

A further object of my invention resides in under-ground air-cooling means of metal having a series of spaced air-deflecting walls or fins to 50 cause a back and forth movement of the air through said air-cooling means and to increase the area of the surface thereof.

A still further object of the invention resides in air-cooling, filtering and humidifying apparatus comprising an air filtering intake unit, an

air blower having air humidifying and heating means, and under-ground air-cooling means connecting said units.

Another object of my invention is found in the provision of an air-cooling conduit provided 5 within the construction of the basement floor of a building or under the basement floor.

Another object of my invention resides in an air-cooling conduit extended preferably in the form of a coil through a body of water, as for 10 illustration, through a coil in a well or cistern.

A still further object of my invention is found in the provision of tubular or rectangular air 15 passages within the walls of a building provided with air outlets into the rooms and air inlets 15 connected to the blower unit.

With the above and other objects in view, my invention consists in the novel combination, construction and arrangement of the parts and members shown in preferred embodiment in the attached drawings, described in the following specifications and particularly pointed out in the appended claims.

• In the drawings:

Fig. 1 is a vertical section through a portion of 25 apparatus embodying my invention showing an application thereof to a building shown in a sectional elevation;

Fig. 2 is a cross-section taken on line 2—2 of 30 Fig. 1;

Fig. 3 is a vertical section through a modified blower unit and air-cooling means;

Fig. 4 is a diagrammatic illustration of one 35 form of air-cooling means shown in Fig. 3;

Fig. 5 is a sectional plan view through the 35 basement of a building showing the air-cooling conduit formed as a part of the basement floor;

Fig. 6 is a cross-section taken on line 6—6 of 40 Fig. 5;

Fig. 7 is a sectional plan view of a portion of a 40 basement of a building and showing an air-cooling conduit extending through the water in a cistern or well, and

Fig. 8 is a cross-section taken on line 8—8 of 45 Fig. 7.

In the illustrations, 10 indicates the walls of a building having a basement floor 11 and upper floors 12. The basement floor 11 is below grade or ground level which is indicated by 13.

As shown in Fig. 1, the building walls are 50 provided with tubular or rectangular ducts indicated respectively by 14 or 15 having outlet openings provided with grills 16.

The apparatus as shown in Figs. 1 and 2 includes an air filtering intake unit generally indi- 55

cated by 17, a blower unit generally indicated by 18 and an under-ground air-cooling means generally indicated by 19.

The air filtering intake unit 17 consists of a housing 20, preferably of metal, having a circular intake 21 extended through a screened opening 22 into the top of housing 20, a circular intake 23 adapted to admit air from within the basement of the building, a floor intake 24 adapted to admit air from within the lower room 25 of the building through a grate 26 in the floor 12 and through an opening in one side of the housing 20.

The air intakes 21, 23 and 24 are each provided with a circular gate valve 27. As shown in Fig. 1, air may be received into the intake housing 20 through any one of the intakes 21, 23 or 24, or through any two of such air intakes or through all three of them by simple manipulation of the valves 27. In Fig. 1 I show air being admitted from outside of the building through intake 21 since the valves 27 for the other two intakes are shown in closed position.

As shown in Figs. 1 and 2, the air intake unit 17 is connected at its rear side with an under-ground air-cooling means shown in the form of a metallic conductor 19 having an extension through the wall of the building and connecting with the housing 20 so that air received into the housing may be passed through the under-ground air-cooling metallic conductor 19 into the blower unit 18. The metallic conductor may be of any suitable metal as for instance copper and preferably provided with spaced air deflecting walls 35 or fins 28 constituting baffles to an interrupted flow of the air through the conductor 19 and providing additional heat conductive surfaces increasing the cooling efficiency of this unit.

One or more removable air filters 29 of any known design may be mounted within the intake housing to filter the air before its passage into the cooling conductor 19.

The air is drawn into and through the intake 20 and through the cooling conductor 19 by means of a fan 30 driven by a motor 31 mounted in the housing 32 of the blower unit 18.

If desirable, the blower unit may be provided with an air filter located between the fan 30 and the outlet of the air-cooling conductor 19.

From within the blower housing 32 the cooled and filtered air may be forcibly discharged through the passage 34 into the conduit 35, which is connected with the rectangular wall conduit 15, and through the grated opening 16 into the room 25, or the valve 36 may be closed and the air discharged through outlet 37 to other parts of the building or the air may be passed through passage 38 and distributed through a lateral conduit 39 for discharge into the rooms through a series of tubular wall passages 14.

Obviously, suitable valves, as for instance valve 36, may be provided for all air distributing channels leading from the blower unit 18 for controlling and regulating the discharge of air to the different rooms. Likewise, the air inlet valves 27 may be operated to provide inlet of air from any one of such inlets, or any two of such inlets or all of the inlets.

In Figs. 3 and 4 I show a modified form of air-cooling means and also show how humidification and air heating means may be provided in the blower unit. One form of humidifying means is indicated by the frame 40 constituting a wick type humidifier which is kept moistened by capillary action through its immersion in the

water tank 41 which is automatically filled with water through the inlet pipe 42 controlled by a float valve 43. The wick type humidifier frame is mounted between the blower fan 30 and the air outlets.

A steam or hot water heating coil 44 is shown positioned between the blower fan 30 and humidifier frame 40 and in the event a hot air heating unit is employed the hot air chamber of the heater may be connected to the blower unit 18 by means of a hot air duct 45 to discharge heated air into the blower unit 18 into a section located between the air filter 33 and the under-ground cool air connections.

Figs. 3 and 4 show an under-ground air-cooling unit comprising substantially semi-circular pipe sections 46 connected together to provide a winding air chamber. To provide sufficient air-cooling surface the pipe sections are placed in a series of connected rows providing adjacent winding passages for the circulation and cooling of the air as shown diagrammatically in Fig. 4. As shown in Fig. 3, the inlet may be in the form of a vertically disposed pipe 46^A extended above the ground surface and terminating in a semi-circular pipe 46^B provided with a screened inlet 47.

Referring now particularly to Figs. 5 and 6, the air filtering intake unit 17 and blower unit 18 are shown diagrammatically in spaced end portions of the basement connected by a winding air-cooling conduit 48 which is disposed between a double basement floor of spaced upper and lower sections, respectively 49 and 50. The upper floor section 49 is supported on air-deflecting walls 51 disposed between the floor sections 49 and 50.

It is obvious that the conduit 48 can be arranged or built in various forms or configurations to provide the desired extended winding air-cooling passage, that is, the path of the air, which is to be cooled, may be arranged to extend in a back and forth or winding manner as between the floor sections 49 and 50 along the sides and around the ends of the walls 51. In Fig. 5, this air-cooling passage is defined by the spaced intermediate parallel walls 51 which extend alternately from one basement side wall 52 toward and to a spaced distance from the other side wall 52 to thus provide alternately arranged end passages 48^A connecting the ends of the parallel passages 48 one with the other. This back and forth movement of the air will extend from the intake floor opening 53 at the bottom of the intake unit 17 to the outlet floor opening 54 at the lower end of the blower unit 18.

It is also contemplated that a similar air-cooling system could be provided under a single basement floor by the use of iron pipes or concrete conduits arranged in a circuitous or winding manner, as for instance, that shown in Figs. 3 and 4.

In the modifications shown in Figs. 7 and 8 I show an air-blower unit 18 similar to that shown in Fig. 3 discharging cooled air through conduits 35, 37 and 38 to the wall tubes 14 and other parts of the building but in the present adaption the air is cooled by its passage through a coiled pipe 55 disposed within the water of a cistern or well indicated by 56. The air cooling coil 55 is connected at the intake end with an air intake pipe 57 extended above the top 58 of the cistern and the outlet end of the coil 55 is connected with the blower unit 18 by any suitable extended pipe 59 preferably extending underground.

I claim:

1. The combination with a building, of air conditioning apparatus comprising an air intake unit, a blower unit, both of said units being mounted within the building, a plurality of air intakes adapted to admit air into said air intake unit from the basement, or room above the basement or from outside of the building, valves for controlling said plurality of air intakes whereby air may be admitted into said air intake unit through one or more or all of said plurality of air intakes, an under-ground air cooling conduit connecting said air intake unit with said blower unit, means for filtering the air passing through said under-ground air cooling conduit, air-heating means in said blower unit, and air-humidifying means between said air-heating means and the air outlet of said blower unit. 5
- 10 2. In a building, air conditioning apparatus comprising an air intake unit, a blower unit, both of said units being mounted within the building, a plurality of air intakes adapted to admit air into said air intake unit from the basement, or room above the basement or from outside of the building, valves for controlling said plurality of air intakes whereby air may be admitted into said air intake unit through one or more or all of said plurality of air intakes, an under-ground air cooling conduit connecting said air intake unit with said blower unit, removable air filtering means at the intake and outlet of said under-ground air cooling conduit, air-heating means in said blower unit, and air-humidifying means between said air-heating means and the air outlet of said blower unit. 15
- 15 20 3. In air cooling apparatus as embodied in claim 2 and including said air cooling conduit constituting a winding conduit formed by a floor spaced below the basement floor of the building and spaced partition walls between said floors, said partition walls being provided with spaced openings to permit the air to pass between said floors in a winding manner from said air intake unit to said blower unit. 20
